UNITED STATES PATENT OFFICE.

OTTO PETERMANN, OF GROTON, NEW YORK, ASSIGNOR, BY MESNE ASSIGNMENTS, TO CORONA TYPEWRITER COMPANY, INCORPORATED, A CORPORATION OF NEW YORK.

TYPE-WRITING MACHINE.

1,193,603.

Specification of Letters Patent. Patented Aug. 8, 1916.

Original application filed June 12, 1909, Serial No. 501,852. Divided and this application filed October 2, 1913. Serial No. 792,894.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing Machines, of which the following is a full, clear, and exact description.

This invention relates more particularly 10 to the tabulating mechanism of visible or front strike typewriting machines of a folding type, and is a division of my application Sr. No. 501,852, filed June 12, 1909, now Patent No. 1,089,345, dated March 3, 1914.

15 One of the principal objects of the invention is to provide simple and efficient means whereby a plurality of stops mounted upon the platen carriage are adapted to engage a part which does not travel with the carriage 20 in its letter spacing movement, and to provide simple means whereby any one of these stops may be engaged to arrest the movement of the carriage along its bed or support.

25 Another object of the invention is to provide simple and efficient means whereby the movement of the carriage along its support while tabulating may be automatically checked against too violent shocks by reason 30 of its sudden engagement with the stopping means.

35 A further object of the invention is to provide simple and efficient means whereby the ribbon mechanism may be entirely cut 40 out of operation during the movement of the carriage while tabulating thus preventing a considerable part of the ribbon from not being used, which results in an unevenly used ribbon.

45 A still further object of the invention is to provide simple and efficient means whereby immediately the escapement is released, the carriage tension means will force the carriage along its bed until stopped, and at the same time disengage both the escapement mechanism and the ribbon mechanism.

With these and other objects in view, the invention will be hereinafter more particularly described with reference to the accompanying drawings, which form a part of this specification, and will then be pointed out in the claims at the end of the descrip-

In the drawings, Figure 1 is a side elevation, partly broken away and partly in section, of one form of machine embodying my invention, showing in dotted lines the upper part of the machine folded over the keyboard. Fig. 2 is a rear elevation of the upper part of the machine. Fig. 3 is a side elevation of the upper part of the machine. Fig. 4 is a longitudinal section, partly in elevation, of the upper part of the machine. Fig. 5 is a detail perspective view of one of the tabulating stops. Fig. 6 is a sectional plan of a part of the escapement mechanism; and Fig. 7 is a fragmentary plan of a part of the carriage propelling mechanism.

While the invention is shown as applied to a typewriting machine in which the platen and carriage is foldable forward into overhanging relation to the keyboard and the invention is ordinarily employed in connection with such machine, it will be understood that many of the features of the invention may be applied to other classes of typewriting or like machines.

The frame 10 may be of any suitable kind and at the rear corners thereof may be arranged brackets 11 in which are adapted to be moved the posts or slides 12 forming a part of the platen shift mechanism. These posts or slides 12 may be attached to or formed integral with horizontally extending arms or bars 13 which are pivoted at 14 to bars or arms 15. The arms or bars 15 are rigidly held to a bed 16, the said bed together with the arms 13 and 14 forming members of a foldable support. A carriage 17 has a base plate 18 arranged over the carriage bed 16 and is adapted to travel lengthwise thereof, there being suitable bearings, as balls 19, interposed between the base plate 18 and the bed 16. The carriage is provided with the usual form of platen 20 and said platen together with the carriage bed is adapted to be folded forward on the pivots 14 so as to invert the carriage and to place the same in overhanging relation to the keys 20^a of the keyboard 21, as shown in dotted lines in Fig. 1.

A vertically movable bar 22 is adapted to be operated by all of the keys 20^a except the platen shift keys as usual. The bar 22 operates an arm 22^a of a two-part lever carrying loose and fixed dogs 23 and 23^a respec-

- tively, which are adapted to engage a ratchet wheel 24 forming a part of an escapement mechanism such as disclosed in my Patent No. 1,121,033, dated December 15, 1914.
- 5 The ratchet wheel 24 is secured to a shaft 24^a supported at one end in a bracket 25 and at its other end extending through the bed 16. This shaft 24^a has a pinion 26 held to rotate thereon and this pinion engages a
- 10 rack 27 mounted upon the carriage base to adapt the carriage under its tension mechanism to be forced for letter spacing when the escapement lever 22^a is operated by the vertically movable bar 22. The carriage is
- 15 connected in any suitable way and at any suitable point by a cord or flexible connection 28 which passes around a spring drum 29 which may be arranged upon one of the bars or arms 15. The connections between
- 20 the keys 20^a and the type-bars as well as the means whereby the bar 22 is operated and also the platen shift mechanism, are not shown herein as they may be of any suitable character.
- 25 The shaft 24^a has a crown wheel 30 held thereto and engaging the crown wheel are bevel pinions 31, Fig. 2, secured to angularly arranged shafts 32, and these shafts operate worms 32^a or other means adapted to rotate
- 30 the gears of the ribbon spools 33 and thus impart a lengthwise movement to the ribbon at each movement of the carriage in letter spacing and when the escapement mechanism is operated during the depression of
- 35 each key-lever. The ribbon spools are located on opposite sides of the machine and one spool is held fast to one spindle while the other spool is loose on its spindle in the usual way. The crown wheel 30 carries a
- 40 member 34 of a two-part clutch. This member 34 has teeth on the upper edge thereof and adapted to engage said teeth are the teeth of a clutch member 35. This clutch member 35 is held to rotate with the pinion
- 45 26 but is movable lengthwise of the hub or sleeve of said pinion. The clutch member 35 is normally forced into engagement with the teeth of the clutch member 34 by means of a spring 35^a, and said clutch member 35
- 50 has a flange 36, the upper surface of which when forced upwardly is adapted to engage the under surface of the bed 16 with a regulated pressure, and as said flange is rotated during the movement of the carriage, the
- 55 said flange will serve as a brake and tend to regulate the sudden movement of the carriage in tabulating and to assist in bringing it to a stop without any unnecessary shock.
- To release the clutch members to permit
- 60 the carriage to move along its bed entirely independent of the movement of the escapement dogs and of the ribbon mechanism, various means may be employed. As shown, a gib or bracket 37 of substantially U-shaped
- 65 form is secured at one end to the carriage
- bed 16 and at the other end thereof carries a screw 38 or other means serving as a guide for the carriage base to hold and guide the latter properly on its bed, and vertically movable in the bracket 37 is a substantially L-shaped arm or slide 39. The arm has one end, as 40, adapted to extend under the lower surface of the flange 36 of the clutch member 34 and is provided with a pin 41 intermediate its ends. The pin 41 normally rests upon the upper edge of a push bar 42 the ends of which are supported in the carriage frame and have beveled or cam-shaped ends 42^a. These ends are movable in slots in the carriage frame and are adapted to cause the bar 42 to move upward when the finger button or knob 43 is pressed on, the said bar 42 being returned to normal position when released by a spring 43^a. When the bar 42 is forced inward the slide 39 will be forced upward and will release the clutch member 35 from the clutch member 34, thus permitting the carriage to move freely along its bed under the tension of the spring drum 29. A lever 44 extends lengthwise of the carriage bed and at the rear thereof. This lever 44 is pivoted at 45 at one end and at its opposite end extends downwardly and enters a slot in the rear end of the lever 46. The lever 46 is pivoted at 47 to one of the arms 45 and at the outer end of said lever is a finger piece or key 48. A pin 49 is held to a second slide or element 50 held to move vertically in the bracket 37 and has a projecting lug 51 movable in a slot 52 in the slide 50 or arm 39 so as to interlock therewith, said slide 50 being normally forced downwardly by a spring 53, one end of which is held to the bracket 37 and the other end is located in a slot in the lower end of the slide 50. The slot 52 is of such a size as will permit the slide 39 to move independently of the slide 50 through the bar 42, but during the movement of the slide 50 through the lever 44 both slides will move in unison. As the key 48 is depressed, the rear end of the lever 46 will raise the lever 44 and the upper edge thereof will engage the pin 49 lifting the slide 50 and arm or slide 39 vertically thus releasing the clutch mechanism and permitting the carriage under its tension drum to force the same along its bed without moving the ribbon mechanism and independent of any engagement of the escapement dogs with the ratchet wheel 24.
- Mounted upon the carriage at the rear thereof is a bar 54. This bar is pivotally held between the carriage frame members or ends and is normally held in one position by a spring 55, the said bar being reduced to form studs in order that it may be properly supported in the carriage frame. On one of the studs at one end of the bar 54 is a lever 56 having an inwardly extending end 57 which is adapted to engage the

inner edge of the carriage frame to position the bar or member 54. The lever 56 opposite the end 57 has a key or finger piece 58 by which the said lever 56 may be depressed 5 in order to swing the bar 54 on its pivot. This bar 54 is provided with a number of vertical slots 59 on one side thereof which are spaced apart to correspond with the teeth of the rack 27 or otherwise. A number 10 of stops are adapted to be detachably held to the bar 54 in such a way that the said stops may be positioned at different points along said bar. As shown, there are four kinds of stops each performing a particular function, that is, there is a marginal stop 60 which may serve also as a trip for the bell, and a line-lock operator, the tabulating stops 61, a regular or usual left hand marginal stop 62, and a final marginal stop 15 63. Each one of these stops comprises a body portion with two inwardly projecting teeth 64, Fig. 5, which are adapted to engage two of the slots of the bar 54, a looped portion 65 forming a spring, and a gripping part 66. The part 64 has its lower end, as 67, formed so as to properly grip the face of the bar opposite the teeth 64 and serves to hold the stops or devices 20 25 detachably to the bar 54, and said stops may have a raised part to engage under one end of the bar 54 to assist in holding the same to said bar. The stop or device 60 has a pendent arm or part 68 which is adapted to engage a part of the hammer of the bell 30 35 to trip the same and cause the bell to ring and also a part of the line lock mechanism, not shown, and when used, and further is adapted to engage the bracket or guide 37 at the extreme movement of the carriage to 40 serve as a stop therefor. Each of the stops or devices 61 has its lower edge beveled and each of said stops is adapted to engage the end or part 69 of the vertically movable slide or member 50 when the latter is moved 45 upward into the path of the same by the operation of the lever 46 when the key 48 is depressed. The stop 62 has a hinged part or member 70 and said stop or device 62 serves as a regular left hand marginal stop and 50 55 this member or part 70 engages the projecting end 69 of the slide 50 when the carriage is moved toward the right to arrest the movement of the carriage. If there is a note on the margin to be written, the lever 56 is depressed so that the bar 54 will be moved on its pivot to permit the stop or device 62 with its member 70 to swing out of the way of the part 69 so that the final stop 63 may come into action, the 60 65 hinged portion or member 70 allowing the stop 62 to move past the projection 69 when the carriage moves to the left in writing. The stop 63 has a pendent portion 71 somewhat shorter than the pendent portion 68 of the other marginal stop and said pendent

portion 71 is adapted to engage the edge of the bracket or guide 37 opposite to the edge thereof engaged by the stop 60.

The construction and operation of the invention will be readily understood from the foregoing description when taken in connection with the accompanying drawings. In depressing the finger piece 48 of the lever 46, the lever 44 is moved upward on its pivot 45 and will engage the pin 49 so as to lift the arm or slide 50. This slide 50 will raise the slide or arm 39 and cause the angular portion 40 thereof to engage the flange 36 of the clutch member 35 and disengage said clutch member from the clutch member 34, thereby permitting the carriage to move quickly in the direction of travel while printing and until one of the stops engages the projection 69 which has also been moved upward as the lever 46 is operated, the escapement mechanism having been released by the disengagement of said clutch. As soon as the lever 46 is released, the projection 69 on the member or slide 50 will be forced downward out of the path of the stops and the teeth of the clutch members will be engaged through the coiled spring 35 arranged under the pinion 26. By depressing the lever 56, the bar 54 may be moved on its pivot to force any one of the stops out of the path of the projection 69 if in engagement therewith so that the carriage can travel quickly to the next stop, providing, of course, that the escapement has been released by the depression of the lever 46 as already explained, in order that the carriage may move freely by reason of the action of the propelling mechanism.

It will be understood that the tabulating stops are easy to set and that the carriage may be folded over and the setting made to scale, for the slotted bar or rail 54 may be provided with a scale on the top side thereof so that the setting of the stops can be made in accordance with the platen scale.

From the foregoing, it will be evident that simple and efficient mechanism is provided whereby various positions of the carriage for tabulating purposes may be readily effected; that the tabulating mechanism is simple in construction and may be employed in connection with various forms of writing machines; that said mechanism is particularly adapted for visible writing machines of the folding type; that the folding means of the carriage permits the tabulating devices to be quickly and readily adjusted or the carriage may be readily folded forward to make the tabulating bar readily accessible for shifting the positions of the different stops; that by the arrangement shown the ribbon mechanism is entirely cut out during the quick movements of the carriage so that no part of the ribbon remains unused; that the main part of the escape-

ment mechanism is also cut out at the same time that the tabulating means is operated; and that simple means is provided to serve as a brake whereby the usual violent impact of the stops against the stationary part of the machine is properly regulated.

Having thus described my invention, I claim as new and desire to secure by Letters Patent:—

1. In a typewriting machine, the combination of a support, a carriage adapted to move along said support, a bar having a rocking movement only on said carriage, a plurality of stops detachably held to said bar, escapement mechanism, means for releasing said escapement only, and a second means coöperating and interlocking with the first-mentioned means for releasing said escapement mechanism, including a part adapted to be moved into the path of said stops.

2. In a typewriting machine, the combination of a support, a carriage adapted to move along said support, a bar having a rocking movement only on said carriage, a plurality of stops of relatively different lengths detachably held to said bar, escapement mechanism, means mounted on the carriage for releasing said escapement mechanism, a second means coöperating and interlocking with the first-mentioned means mounted on the support for releasing the escapement and including a part adapted to be moved into the path of certain of said stops, and means adapted to be engaged by other of said stops to arrest the movement of the carriage.

3. In a typewriting machine, the combination of a support, a platen carriage adapted to travel along said support, a stop bar pivotally held to said carriage at the rear thereof, means for moving said bar on its pivot, a plurality of stops of relatively different lengths adapted to be held to said bar, a relatively stationary part located on the support adapted to be engaged by certain of said stops, a movable element adapted to engage certain of said stops and guided in said stationary part, escapement mechanism, and means to release said escapement mechanism and move said stop engaging element.

4. In a typewriting machine, the combination of a support, a platen carriage adapted to travel along said support, a slotted stop bar pivotally held to said carriage at the rear thereof, a lever for moving said bar on its pivot, a plurality of stops detachably held to said bar, a relatively stationary part adapted to be engaged by certain of said stops, a vertically movable element adapted to engage certain of said stops and guided in said stationary part, escapement mechanism, and a second interlocking element adapted to release said

escapement mechanism and adapted to be moved when the first-mentioned element is moved or independently of said first-mentioned element.

5. In a typewriting machine, the combination of a support, a platen carriage adapted to travel along said support, a slotted stop bar held to said carriage, a plurality of stops detachably held to said bar, a relatively stationary part mounted on the support adapted to be engaged by certain of said stops, feed mechanism, and two relatively movable interlocking members one adapted to co-operate with the other as means to release said feed mechanism and to engage any one of said plurality of stops and arrest the movement of the carriage and the other as escapement releasing means only.

6. In a typewriting machine, the combination of a keyboard, a support movable forwardly into substantially overhanging relation to the keyboard, a carriage movable along the support and into overhanging relation therewith, and tabulating mechanism comprising stops mounted at the rear of the carriage and a coöperating stop carried by the support, said tabulating mechanism as an entirety thereby partaking of the forward movement of the carriage and support and bringing the stops into more accessible position.

7. In a typewriting machine, the combination of a support, a carriage adapted to move along said support, escapement mechanism, tabulating mechanism, means adapted to operate on the escapement mechanism to permit the carriage to travel freely along its support, and a second means forming a part of the tabulating mechanism and interlocking and coöperating with the first-mentioned means to release the escapement.

8. In a typewriting machine, the combination of a support, a carriage adapted to move along said support, escapement mechanism, tabulating mechanism located at the rear of the machine and having a part thereof movable with the carriage, means adapted to operate on the escapement mechanism to permit the carriage to travel freely along its support, and a second means mounted on the support and including a slide forming a part of the tabulating mechanism and interlocking and coöperating with the first-mentioned means to release the escapement.

9. In a typewriting machine, the combination of a platen carriage, a movable element located at the rear of the carriage, escapement mechanism adapted to be released by said movable element, a second movable element located adjacent to the first-mentioned element, a lever extending lengthwise of the carriage and pivoted at one end and adapted to actuate said movable element, a pivotally held lever adapted to move the first-mentioned lever to release the escape-

ment and to move a part of said second element upward, and a plurality of stops movable with the carriage adapted to engage the part of said movable element.

5 10. In a typewriting machine, the combination of a support, a platen carriage, escapement mechanism, a movable element located at the rear of said carriage, a bracket in which said element is guided, a lever extending lengthwise of the carriage and adapted to move said element, a pivotally held lever located at one end of the support and having a finger part extending forward, said latter lever being adapted to move the 10 first-mentioned lever to release the escapement and to move a part of said element upward, and a plurality of stops movable with the carriage adapted to engage a part of said movable element.

15 20. 11. In a typewriting machine, the combination of a support, a platen carriage adapted to move along said support, a movable element located at the rear of the carriage and mounted on the support, escapement mechanism adapted to be released by said movable element, a second movable element interlocking with the first-mentioned element and adapted to actuate said first-mentioned element, means for actuating said elements together or one of them independently of the other, and a plurality of stops movable with the carriage adapted to engage a part of one of said movable elements.

25 30. 12. In a typewriting machine, the combination of a platen carriage, a slide located at the rear of said carriage, a separable escapement mechanism adapted to be engaged by said slide to separate the same to permit the carriage to move freely along its support, a second slide interlocking with the first-mentioned slide and adapted to actuate said first-mentioned slide, a spring normally forcing the second slide downward, a lever mounted on the support and located at the 35 rear of and extending lengthwise of the carriage and adapted to engage a part of said second slide, a pivotally held lever having a finger key and adapted to move the first-mentioned lever to release the escapement and to move a part of said second slide upward, and a plurality of stops movable with the carriage adapted to engage a part of said second slide.

40 45. 13. In a typewriting machine, the combination of a support, a carriage adapted to travel along said support, escapement mechanism, means including two vertically movable interlocking slides for releasing said escapement mechanism, a pivotally held bar, a lever for moving said bar on its pivot, and a plurality of stops movable with the carriage and adapted to engage a part of one of the slides.

50 55. 14. In a typewriting machine, the combination of a platen carriage, a movable ele-

ment, escapement mechanism adapted to be released by said movable element, a second movable element, a lever extending lengthwise of the carriage and pivoted at one end and adapted to actuate said movable element, a pivotally held lever adapted to move the first-mentioned lever to release the escapement and to move a part of said second element upward, and a plurality of stops movable with the carriage adapted to engage the part of said movable element.

55 60. 15. In a typewriting machine, the combination of a support, a platen carriage, escapement mechanism, a movable element, a lever extending lengthwise of the carriage and adapted to move said element, a pivotally held lever located at one end of the support and having a finger part extending forward, said latter lever being adapted to move the first-mentioned lever to release the escapement and to move a part of said element upward, and a plurality of stops movable with the carriage adapted to engage a part of said movable element.

65 70. 16. In a typewriting machine, the combination of a support, a platen carriage, a movable element, escapement mechanism adapted to be released by said movable element, a second movable element adapted to actuate the first-mentioned element, means for actuating said elements together or one of them independently of the other, and a plurality of stops movable with the carriage adapted to engage a part of one of said movable elements.

75 80. 17. In a typewriting machine, the combination of a platen carriage, a slide, a separable escapement mechanism adapted to be engaged by said slide to separate the same to permit the carriage to move freely along its support, a second slide adapted to actuate the first-mentioned slide, a spring normally forcing the second slide downward, a lever located at the rear of and extending lengthwise of the carriage and adapted to engage a part of said second slide, a pivotally held lever having a finger key and adapted to move the first-mentioned lever to release the escapement and to move a part of said second slide upward, and a plurality of stops movable with the carriage adapted to engage a part of said second slide.

85 90. 18. In a typewriting machine, the combination of a support, a carriage adapted to travel along said support, escapement mechanism, a pivotally held bar mounted at the rear of the carriage, a finger operated lever for moving said bar on its pivot, and a plurality of stops mounted on said bar and adapted to engage a part of the escapement releasing means.

95 100. 19. In a typewriting machine, the combination of a support, a carriage adapted to travel along said support, escapement mech-

anism, means for releasing said escapement mechanism, a pivotally held slotted bar mounted on the carriage at the rear thereof, a finger operated lever held at one end of the bar at one end of the carriage for moving said bar on its pivot, and a plurality of stops detachably held to said bar and adapted to engage a part of the escapement releasing means.

- 10 20. In a typewriting machine, the combination of a support, a carriage adapted to travel along said support, escapement mechanism, means including two vertically movable slides for releasing said escapement mechanism, a pivotally held bar, a lever for moving said bar on its pivot, and a plu-

rality of stops adapted to engage a part of one of the slides.

21. In a typewriting machine, the combination of a support, a carriage adapted to travel along said support, carriage feed mechanism, a two-part clutch forming a part of said mechanism, and means for releasing the clutch and causing the flange to rub against a part of the support to serve as a 25 brake.

This specification signed and witnessed this 29th day of September, A. D. 1913.

OTTO PETERMANN.
